Attorney

UNITED STATES PATENT OFFICE

ARTHUR F. BERNARD, OF PROVIDENCE, RHODE ISLAND

STRAP-END-CONNECTING MEANS

Application filed October 12, 1929. Serial No. 399,343.

My invention relates to improvements in means for fixedly attaching a strap end to an article having bar means thereon for attachment thereof to said strap. This application 5 is in part a true divisional application and a continuation in part of my application for strap buckles, filed October 11, 1928, Serial Number 311,852.

An object of my invention is to provide 10 means for permanently attaching a strap end to an article such as a wrist watch having bar means thereon for attachment of a strap end thereto. While my invention may be employed with any type of a strap it is preferably employed in combination with a strap 15 having an automatic strap tightener of the type shown in said application. My invention is adapted for use in an article wherein the bar means thereof is permanently attached thereto and is particularly adapted for 20 use in an article wherein the bar means thereof are detachably secured thereto.

These and such other objects of my invention as may hereinafter appear will be 25 best understood from the description of the accompanying drawings.

In the drawings, Fig. 1 is a perspective view of a wrist watch bracelet wherein my improved attaching means is employed to attach 30 both ends of the bracelet or strap to the bar means employed on the opposite ends of the wrist watch.

Fig. 2 is a disassembled rear perspective view of the attaching means and the bar 35 means of the wrist watch.

Fig. 3 is a longitudinal sectional view taken through the attaching means in attached position permanently attaching the strap end to the wrist watch bar.

40 Fig. 4 is a disassembled rear perspective view similar to Fig. 2 wherein the bar means on the wrist watch is detachably securable thereto, partially shown in section.

In the drawings, wherein like characters 45 of reference indicate like parts throughout, 10 generally indicates a strap adapted to encircle the wrist. Said strap may be constructed of leather, woven wire or any suitable material. 12 generally indicates the 50 wrist watch interposed in the circumference

of said strap, said wrist watch being provided with transversely extending bar means 13, projecting from each end thereof for attachment of each strap end thereto. Though I have shown my invention in use for attachment for both ends of the strap to a wrist watch or other article having bar means attached thereto, it is obvious that my improved device may be employed for attaching any type of strap to any type of article 60 having bar means for this purpose attached thereto. As shown in the drawings, I preferably provide the improved strap tightener 16 shown and claimed in my aforesaid application, though it is obvious that my invention 65 may be employed for attaching any type of a strap end to such an article.

Said strap 10 is provided with the ends 24 and 48 and the wrist watch 12 is as stated provided with the bar means 13 aforesaid. 70 My invention consists of the improved means I employ to fixedly attach each end 24 and 48 respectively of said strap 10 to its respective bar means 13. My improved type of attaching means to fixedly attach each end of said strap to the bar means 13 comprises the plate member 60 having the bar receiving preferably pliable downwardly projecting hook 62 at the outer end thereof, bent over to form the curved bill 63, and body 65 preferably provided with the central slit 64 in the bill 63 thereof. Said member 60 has a strap clamp 66 pivoted to the rearwardly projecting side flanges 68 thereof at the inner end thereof, said clamp having preferably a toothed edge 80 75 85 90 95 100 to clamp the strap end 24 against said member 60 and an outwardly projecting tongue 72 rearwardly curved as at 74 and preferably having a finger nail operative portion 76 projecting outwardly therefrom adapted to pivot rearwards through said slit 64 in the bill of said end hook 62 and adapted to be permanently retained in locked position under said bar means 13 within and between the bill 63 and body 65 of said hook 62. As shown more particularly in Fig. 3, the hook 62 is preferably pliable so that on insertion of said bar means 13 therein said hook may be further bent over said bar means to bring the bill 63 thereof closer to the body 65

thereof to more securely bind said strap end to said bar means.

If desired, however, I may employ a bar means of a type which may be detachably secured to said article. In this case as shown in Fig. 4 the article is provided with the outwardly projecting spaced lugs 80 each having the transverse pivot holes 82 therein. Said bar means 13 is provided with the pintles 84 and 86 projecting outwardly from each end thereof. The pintle 84 is preferably resiliently mounted within the hollow interior 88 of one end of said bar means 13 and is provided with the enlarged piston head 90 within the hollow portion of said bar means adapted to be resiliently urged outwardly by the spring 92 contained within the hollow portion of said bar means. It is thus obvious that if a detachable bar means of this type be employed that the bar means 13 may first be slid longitudinally within said hook 62 over the tongue 76 thereof and then that said pintles 84 and 86 of said bar means 13 may be detachably secured within the pivot holes of said lugs 80 by depression of the resiliently mounted pintle 84 during insertion of said pintles within said pivot holes 82 and it is also apparent that by employing this construction the bill 63 of the hook 62 need not be made pliable or bent over afterwards to firmly overlap the bar means 13 to securely bind the strap end 24 to said article 12 with the portion of said tongue retained underneath said bar means 13 within and between the bill 63 and body 65 of said hook 62.

It is understood that my invention is not limited to the specific embodiments shown and that various deviations may be made therefrom without departing from the spirit and scope of the appended claims.

What I claim is:

1. Means to fixedly attach a strap end to an article having bar means for attachment thereof to said strap end comprising a member having a bar receiving downwardly projecting hook having a bill and a body and having a slit in the bill thereof, a strap clamp pivoted to said member at the inner end thereof having a portion to clamp the end of said strap against said member and an outwardly projecting rearwardly bent tongue having an operating portion adapted to pivot downwards through said slit in the bill of said end hook and of a length to extend and to be permanently retained in locked position under said bar means within and between the bill and body of said hook.

2. Means to fixedly attach a strap end to an article having bar means for attachment thereof to said strap end comprising a member having a pliable bar receiving downwardly projecting hook at the outer end thereof having a bill and a body having a slit in the bill thereof, a strap clamp pivoted to said member at the inner end thereof having a portion to have a

tion to clamp the end of said strap against said member and an outwardly projecting rearwardly bent tongue having an operating portion adapted to pivot downwards through said slit in the bill of said end hook of a length to extend and to be permanently retained in locked position under said bar means between the bill and body of said hook, whereby after insertion of said bar means within said pliable hook said bill may be bent to closely bind said bar means within and between the bill and body of said hook.

3. Means to fixedly attach a strap end to an article having bar means for attachment thereof to said strap end comprising a member having a bar receiving downwardly projecting hook having a bill and a body at the outer end thereof, a strap clamp pivoted to said member at the inner end thereof having a portion to clamp the end of said strap against said member and an outwardly projecting rearwardly bent tongue of such length as to extend and to be permanently retained in locked position under said bar means within and between the bill and body of the hook.

4. Means to fixedly attach a strap end to an article having bar means for attachment thereof to said strap end comprising a member having a pliable bar receiving downwardly projecting hook at the outer end thereof having a bill and a body, a strap clamp pivoted to said member at the inner end thereof having a portion to clamp the end of said strap against said member and an outwardly projecting rearwardly bent tongue of such a length as to extend and to be permanently retained in locked position under said bar means within and between the bill and body of said hook whereby after insertion of said bar means within said pliable hook, said bill may be bent to closely bind said bar means within and between the bill and body of said hook.

5. In combination, an article having spaced lugs projecting therefrom, bar means adapted to be detachably secured between said lugs and means to fixedly attach a strap end to said bar means comprising a member having a bar receiving downwardly projecting hook at the outer end thereof having a bill and a body and having a slit in the bill thereof, a strap clamp pivoted to said member at the inner end thereof having a portion to clamp the end of said strap against said member and an outwardly projecting rearwardly bent tongue having an operating portion adapted to pivot downwards through said slit in the bill of said end hook and of a length to extend and to be permanently retained in locked position under said bar means within and between the bill and body of said hook, whereby said attaching means may be attached to said bar means without bending the bill of the hook thereof.

6. In combination, an article having

spaced lugs projecting therefrom, bar means adapted to be detachably secured between said lugs and means to fixedly attach a strap end to said bar means comprising a member having a bar receiving downwardly projecting hook at the outer end thereof having a bill and a body, a strap clamp pivoted to said member at the inner end of said hook having a portion to clamp the end of said strap against said member and an outwardly projecting rearwardly bent tongue of a length to extend and be permanently retained in locked position under said bar means within and between the bill and body of said hook.

15 In testimony whereof I affix my signature.
ARTHUR F. BERNARD.
